UNITED STATES PATENT OFFICE.

HENRY J. F. T. KACKER, OF BIRMINGHAM, ALABAMA.

BAG-CLEANING MACHINE.

Application filed January 6, 1921. Serial No. 435,529.

To all whom it may concern:

Be it known that I, HENRY J. F. T. KACKER, a citizen of the United States of America, residing at Birmingham, in the 5 county of Jefferson and State of Alabama, have invented certain new and useful Improvements in Bag-Cleaning Machines, of which the following is a specification.

This invention relates to a bag cleaning 10 machine of the type comprising a slatted rotating drum into which the bags to be cleaned are introduced and which is rotated with internal elements designed to raise the bags and to cause them to drop so that the 15 dust and dirt therein will be beaten out against the slatted walls of the drum and will escape therefrom.

In a device of this character it is of prime 20 importance that the drum be designed to avoid tearing or excessive wear on the bags and to this end my drum is formed with internal slatted shelves of such shape as to present no sharp edges against which the sacks may fall and over which they will 25 be drawn and which will be of such character as to avoid collecting and holding the sacks thereon after a shelf rises appreciably from its lowest level, to the end that the sacks may all be collected in one pocket 30 formed between the lowermost shelves.

Another further feature of my invention 35 is the provision of a bag cleaning apparatus of the type above described with a door in its peripheral walls so arranged between shelves as to permit of the most convenient 40 removal of the bags when collected in the pocket between such shelves, thus permitting all bags to be withdrawn at the same time and without having to get into the drum to 45 clean out the pockets.

A further object of my invention is to 50 simplify and perfect the manner of constructing a slatted drum comprising middle rings to reinforce the longitudinal slats and 55 to carry the intermediate supports for the internally projecting slatted shelves.

A further object is to simplify the construction by attaching the slats to the outside periphery of the end rings carrying the 60 end slats and to the inside peripheries of the intermediate reinforcing rings.

My invention further comprises the novel 65 details of construction and arrangements of parts, which in their preferred embodiment only are illustrated in the accompany-

ing drawings which form a part of this specification, and in which:

Fig. 1 is a side elevation of my apparatus.

Fig. 2 is a half end view and half cross 60 sectional view of the drum.

Fig. 3 is a partial plan view of an end ring; and

Fig. 4 is a partial plan view of an intermediate ring, with parts of the slats shown 65 in both views.

Fig. 5 is a detail view of the door latch.

Similar reference numerals refer to similar parts throughout the drawings.

As illustrated, my invention comprises a 70 drum of large diameter mounted on a central shaft 1 which turns in bearings 2 carried by supports 3 of any suitable character. The drum may be driven by any suitable source of power, not shown. The ends of the drum, which are alike, comprise 75 a pair of spaced hub plates 4 and 5 which are fast on the shaft 1 and have bolted between them radial spokes 6 which extend to the periphery of the ends and are there received between curved spacing strips 7 80 (Fig. 3), which form with the intervening spokes an annular rim, to the inside face of which is bolted a second annular ring formed of curved spacing strips 8 and interposed shelf blocks 9, the segments of the inside 85 rim being disposed at break joints with the outside rim and the parts cross connected by bolts 10 between spokes and by bolts 11 through the spokes. I show four of the shelf blocks, arranged equi-distantly about 90 the rim and each having its edges that project towards the hub sloping at an angle of nearly 135° to the spokes. One spoke is bolted at the apex and base of each of these blocks, and for the sake of lightness 95 the center of the block may be cut away. The walls of the block are thus inclined so as to rise at a gentle slope from the inner periphery of the rim for the purposes herein-after described. The two skeleton end frames 100 formed by the spokes are covered by spaced slats 12 and 13, the former being arranged about the outer zone of the frame and each subtending three spokes, while the inner slats 13 fill in the space between the slats 12 and the hub plates and are arranged to 105 connect different groups of three spokes from those which are connected by the slats 12. This arrangement of the slats 12 and 13 to connect different groups of three 110

spokes gives greater strength and rigidity to the end frames. As both of these end frames are alike, the description of one applies to both. The two end frames are cross connected by longitudinal spaced slats 14 which extend continuously from end to end of the drum, those which are attached to the end rims between the shelf blocks having their inside faces notched so that their reduced ends 15 overlap the outside periphery of this part of the rim and are attached thereto. The slats opposite the shelf blocks are attached to the inside faces of the shelf blocks so that the internal slatted periphery of the surface of the drum is formed by a continued series of slats resting partly on the inside faces of the shelf blocks and partly on the outside faces of the rim between the blocks, the slats as a whole forming a continuous inclosure with their exposed inner faces rounded and presenting at no point a sharp angle or flat face to the articles within the drum to be cleaned.

In view of the capacity to be obtained from the drum and the lightness of the slats, it is desirable to provide them with intermediate braces and this I do by the provision of two intermediate laminated rings indicated generally by the reference numeral 16 and each formed by an outside series of curved bars or segment plates 17 between which and at break joints therewith are an inner series of curved bars or segment plates 18. To the latter are attached the four intermediate shelf blocks 19, which have their inner faces lying in the same plane with the inner sloping faces of the end shelf blocks 9. These intermediate shelf blocks are shown as slotted blocks slightly deeper than the blocks 9 by reason of the fact that the inside diameter of the ring 16 corresponds exactly with the diameter of a circle with its periphery lying in the plane of the outside edges of the notched ends 15 of the slats intervening between the shelf blocks. The purpose of this arrangement is to enable a slat to be suitably attached to the inside periphery of the reinforcing rings 16 and to the outside periphery of the end rings, thus leaving the interior of the drum entirely free of any projection thereinto. At the same time these rings 16, which are relatively light, possess much strength and very effectively reinforce the intermediate zone of the drum.

The drum is provided with a door arranged between the rings 16, the door being formed by slat sections 20, each forming a continuation of parts of slats 14 which extend from each ring 16 to the adjacent end of the drum. These door slats 20 are screwed to back metallic straps 21 which at one end are provided with an eye 22 through which a pivot bolt 23 is passed, the bolt being continued through the two rings 16 and secured thereby in position. These straps

have their free ends slotted at 24 and these slotted ends are adapted to pass over staples 25 carried by a bar 26 which is attached to the inside of the rings 16 with its inner edge lying below the surface of the 70 adjacent slats 14. The door is fastened in its lowered position by means of a fastener rod 27 having a bifurcated end 28 in which is pivotally mounted a keeper plate 29 free to swing at right angles to the rod 27, and when moved into alignment with the rod forming a piece flush therewith which can be inserted through the openings in the staples 25. The length of the rod, with reference to the spacing between the rings 16, is such that it can only be introduced by slipping its unslotted end first through the right hand staple (Fig. 1) and when its left hand end can be moved into alignment with the left hand staple 25, whereupon the bar is shifted to the left until the keeper 29 is passed through the opening in the left hand staple 25 and then the keeper is brought at right angles. Under these conditions the space between the left hand end of the rod and the adjacent ring 16 is too short to permit the right hand end of the rod to clear the right hand staple and as the rod, by reason of the keeper, cannot become disengaged from the left hand staple 25 I thus provide a very simple latch which has the requisite strength and simplicity and yet which cannot work loose.

Bearing in mind that the gentle slope of the shelves is such that bags and articles, 100 when the drum is at rest, will not hang thereon after a shelf has swung upwardly through an angle of approximately 90° from its bottom-most position, it will be apparent that when the drum comes to rest all 105 of the sacks therein will fall to the bottom and can be caused to collect in one of the pockets formed between the adjacent lowermost shelves. The drum is turned until this pocket is the one in which the door is 110 provided and by this arrangement the operator, without entering the drum, can remove all of the sacks or other articles there-in that have been cleaned and can do it 115 quickly and easily, it being possible to reach either end of the drum through the door opening. As the drum is rotated, however, it will be apparent that as its speed increases the centrifugal force opposes the 120 tendency of the sacks to fall quickly off of the shelves and at normal operating speed causes the sacks to be lifted to the top of the drum where they get the full length drop onto the bottom slats, which drop is the means upon which I rely for their effective 125 cleaning. By reason of the fact that there is no sharp edge or corner against which a sack may fall or over which it may be drawn, it is obvious that the sacks are effectively protected from wear in the drum. 130

Having thus described my invention, what I claim as new and desire to secure by Letters Patent, is:—

1. A rotatable cleaning drum mounted to rotate about its longitudinal axis and having its interior wall formed by longitudinal slats mounted at intervals on inwardly projecting gradually sloping substantially symmetrical spaced shelves which provide longitudinal pockets, each having a wide arcuate bottom wall and divergent gradually sloping walls, the sloping walls of each shelf being disposed at an obtuse angle and meeting in a rounded top edge, and a rotatable frame 10 work for supporting said slats.
2. A cleaning drum comprising end walls having a rim carrying inwardly projecting shelf blocks, intermediate rings of greater diameter than the end rim and having inwardly projecting shelf blocks with sloping faces lying in the same plane with aligning end shelf blocks, longitudinal slats extending from end to end of the drum and attached to the outer periphery of the end rim 20 and the inner periphery of the intermediate rings and also attached to the aligning faces of the intermediate and end shelf blocks, and means to rotate the drum.
3. A cleaning drum comprising end walls having a rim carrying inwardly projecting shelf blocks, intermediate rings of greater diameter than the end rim and having inwardly projecting shelf blocks with sloping faces lying in the same plane with aligning 30 end shelf blocks, longitudinal slats extending from end to end of the drum and attached to the outer periphery of the end rim and the inner periphery of the intermediate rings and also attached to the aligning faces 40 of the intermediate and end shelf blocks, and means to rotate the drum, there being two intermediate rings and a door interposed between said rings.
4. A sack cleaner comprising a slatted drum formed by end slatted walls having peripheral rims and internally projecting shelf blocks, intermediate rings of greater diameter than the end rim and having inwardly projecting shelf blocks with sloping 45 faces lying in the same plane with similar aligning end shelf blocks, and longitudinal slats having their inner faces round, which slats are attached to the inner periphery of the rings and have their ends notched for

attachment to the outer periphery of the end rims, said slats being also attached to the outer faces of the aligning shelf blocks on the rings and end rims of the drum, a slatted door interposed in the drum periphery, and rotatable supports for the drum. 55

5. A bag cleaning machine having end frames formed by hubs, spokes radiating from the hubs, curved spacer blocks interposed between the outer ends of the spokes, and break joint plates attached to said spacer plates, part of said breaker joint plates forming inwardly projecting shelf supports, slats about the outer zone of the end frame, each connecting a group of three spokes, and other slats about the inner zone 60 of the end frame, each of which connects a different group of three slats from those that are connected by the slats in the outer zone, and a slatted drum body mounted on the drum ends, substantially as described. 65

6. A drum mounted to rotate about its longitudinal axis comprising slatted end walls and a body formed by longitudinal slats connected to the end walls and arranged to form at intervals substantially symmetrical relatively shallow pockets, the bottom walls of which form substantial sectors of a cylinder and the side walls of which diverge in gradually sloping planes to form widely spaced inwardly projecting shelves rounded over their apices and having gently sloping side walls forming between them an obtuse angle. 75

7. A drum mounted to rotate about its longitudinal axis comprising slatted end walls and a body formed by longitudinal slats connected to the end walls and arranged to form four equally spaced symmetrical relatively shallow pockets, the side walls of which diverge in flat planes at a gradual 80 slope to form inwardly projecting shelves rounded over their apices and having gently sloping flat side walls forming between them an obtuse angle adapted to cause sacks that collect thereon to fall off by gravity from 85 all shelves lying with their apices in or above the horizontal central plane through the drum. 90

In testimony whereof I affix my signature.

HENRY J. F. T. KACKER.
